(57) **CLAIM**

The ornamental design for a heat-insulating container, as shown and described.

DESCRIPTION

FIG. 1 is a perspective view of a heat-insulating container showing my new design;

FIG. 2 is a front view thereof, the opposite rear view being mirror image thereof;

FIG. 3 is a top plan view thereof;

FIG. 4 is a bottom view thereof;

FIG. 5 is a left side elevation thereof, the opposite right side elevation being mirror image thereof;

FIG. 6 is a perspective view of a container body thereof;

FIG. 7 is a front view of a lid body thereof;

FIG. 8 is a top plan view of the lid body thereof;

FIG. 9 is a bottom view of the lid body thereof;

FIG. 10 is a front view of a lid cover thereof; and,

FIG. 11 is a bottom view of the lid cover thereof.

The container body, lid body and lid cover are shown separately for clarity of illustration.
